UNITED STATES PATENT OFFICE.

CYRUS R. CRANE, OF HOUSATONIC, MASSACHUSETTS.

WASHING-MACHINE.

SPECIFICATION forming part of Letters Patent No. 395,037, dated December 25, 1888.

Application filed August 26, 1886. Serial No. 211,920. (No model.)

To all whom it may concern:

Be it known that I, CYRUS R. CRANE, of Housatonic, in the county of Berkshire and State of Massachusetts, have invented a new 5 and Improved Washing-Machine, of which the following is a full, clear, and exact description:

My invention relates to a power washing-machine designed for use particularly in various bleaching operations wherein the fabrics are treated in continuous lengths; and my invention consists of a method of washing and a machine constructed as hereinafter described and claimed.

Reference is to be had to the accompanying drawings, forming part of this specification, in which similar letters of reference indicate corresponding parts in all the figures.

Figure 1 is a side elevation of the washing-machine, showing two of the series of tanks and a part of another, and showing the water-main or service-pipe in dotted lines. Fig. 2 is a similar view of the opposite side of the machine, showing the waste-water pipe in dotted lines. Fig. 3 is a longitudinal sectional elevation of the machine, taken on the line *x x* of Fig. 4, the dotted line *w* indicating the fabric. Fig. 4 is a transverse sectional elevation taken on the line *y y* of Fig. 2, and Fig. 5 is a perspective view of one of the spreaders or distributors for spreading the water as it enters the bottom of each tank from the water-supply pipe.

A represents a long narrow tank separated 35 by the transverse partitions C to form a series of compartments or small tanks, B. At the bottom of each tank B is admitted a forced supply of water from the service-pipe D through the branch pipes E. The water thus 40 admitted to each tank B rises to a point near the top thereof, where it is discharged through the overflow-pipes F, and in order to effect a uniform flow of water through the tanks from the inlet to the overflow, especially in the center of each tank, where the fabric is subjected 45 to the action of the water-currents, I use a discharge of considerable length, consisting in this instance of an elongated perforated rose or shell, G, placed over the entrance to the discharge-pipes F, thus preventing all eddying or centralization of the water-currents at any part of the tank; and to still further

equalize the currents of water in the tanks, so the water will have uniform action upon all parts of the fabric, I cause the water to be divided into small streams, and in this instance and for this purpose I place a perforated false bottom, H, in each tank B, under which the water enters, as will be understood from Fig. 4, and the entering water is spread as it enters over nearly the entire area of the tank—in this instance by a spreading device or hood, J. (Shown in Figs. 4 and 5.) In this manner the fabric is subjected in each tank to a uniform current washing or rinsing action of 65 clear water, the water being continuously admitted to and discharged from each tank.

At each end of the machine is located a feed-roller, K, and over each partition C is located a transfer-roller, L, for transferring 70 the fabric from one tank B to the other. These rollers K L are of uniform size and are revolved at a uniform speed from the shaft M and the sets of beveled gear-wheels N O.

In operation the fabric is fed back and forth 75 through the machine and washed many times without handling and without detaching it from the machine, and for this purpose the rollers K L are reversed in their revolution—in this instance by reversing the motion of 80 the shaft M, which is accomplished by shifting the two belts P Q on the pulleys R S T. The belt P is a crossed belt, while the belt Q is a straight belt, so they will impart reverse motion to the shaft M when shifted, respectively, to run upon the pulley S, which is fast upon the shaft. The pulleys R T are loose upon the shaft M, and the belts P Q are shipped simultaneously by the belt-shipper U, so that while the belt Q is on the pulley T 90 the belt P will run upon the pulley S, and when the belt Q is shipped to the pulley S the belt P will be shipped to the loose pulley R, and thus reverse the action of the machine. When the belts P Q run upon the pulleys R 95 T, respectively, the machine will remain at rest.

Upon the rollers K L rest the rollers V, which insure the positive feed of the fabric and which press or squeeze the water from the 100 fabric as it passes from one tank to the other and as it passes out of the machine. With some fabrics the rollers V will not be used, as the drawing of the fabric over the rollers L will

sufficiently expel the water. The rollers V are journaled in vertically-sliding bearings d, which are constantly pressed downward by the springs W, the pressure of which may be 5 adjusted by the screws W', fitted in the cross-pieces W², and which bear at their lower ends upon the springs, as shown clearly in Fig. 4, so that by turning the screws W' the pressure upon the fabric may be easily regulated.

10 D' D² are guide pieces or rollers located near the bottom of each tank B for submerging the fabric and for guiding the fabric from the bottom of the tank to the rollers K or L, as the case may be, and above each guide piece 15 or roller D' D² is secured a guide, D³, formed with a long narrow opening, d', through which the fabric passes for keeping the fabric central in the machine.

In operation the fabric is introduced at one 20 end of the machine and several folds permitted to accumulate in the first tank B. Then the end of the fabric is passed under the guide-roller D² at the opposite corner of the tank, carried up through the guide D³, and 25 passed over the roller L to the next tank B. Here several folds are permitted to accumulate, as shown in dotted lines in Fig. 3, and then the end is passed under the roller D² and up through the guide D³, over the next roller 30 to the next tank, and so on through the whole series of tanks. The rollers being of uniform size and revolved at a uniform speed, the fabric will be continuously fed through the machine and subjected in each tank to the currents of clean water, and in passing over the rollers L the water will be successively expelled from the fabric previously to entering each tank. The fabric having passed through 35 the machine in one direction, the belts O P will be shifted and the rollers K L reversed, and the end of the fabric introduced at the opposite end of the machine and passed from tank to tank and under the rollers D' in each tank, accumulation of the fabric being permitted in each tank the same as in the opposite action of the machine. In this manner 40 the fabric may be passed back and forth through the machine as often as required to 45

thoroughly cleanse it, without the necessity of handling the goods and without material delay, and the fabric is subjected for a considerable length of time in each tank to a thorough rinsing action in forced currents of pure water, and in passing over the rollers L the water contained in the fabric is expelled, 50 so the water of one tank will not be contaminated by the water in the tank through which the fabric has already passed, and this expulsion of the water greatly facilitates the cleaning of the fabric.

60 By providing each tank B with a separate water-supply and separate overflow, so that the water of one tank is not contaminated by the water of another, it will be seen it is practical to reverse the action of the machine and 65 work the goods back and forth, as there is no universal or general contamination of the water, as where the water of one tank is carried to another.

Having thus fully described my invention, 70 what I claim as new, and desire to secure by Letters Patent, is—

1. In a washing-machine, a series of tanks, B, each having a separate water-supply and 75 separate overflow, and each provided with submerging-rollers, the rollers K L L, and upper rollers, V, in combination with means for revolving the rollers K L L first in one direction and then the other for conveying the fabric back and forth through the machine, 80 substantially as described.

2. The washing-tanks B B, provided with separate water-supply pipes, in combination with elongated and horizontal-wastes G, arranged near the top of the tanks to prevent 85 centralization of the water-currents, substantially as described.

3. The tank B, provided with a water-supply pipe, E, and elongated overflow G, in combination with the perforated false bottom H 90 and spreader J, substantially as described.

CYRUS R. CRANE.
